POSTING TRAY

Samuel Segal, New York, N. Y., assignor to Wilson-Jones Co., Chicago, Ill., a corporation of Massachusetts

Application November 2, 1945, Serial No. 626,316

21 Claims. (Cl. 129—16)

1

The subject matter of the invention is an improved and serviceable posting tray generally utilized to sustain a stack of record sheets in an orderly and clamped relation or in an appropriate unclamped relation to facilitate finger manipulation of the several sheets of the stack without however disturbing the proper order or classification thereof. Specifically the invention may be said to be directed to a simplified and expandable filing and posting tray for loose leaf sheets, index cards, ledger sheets, correspondence and other important documents to which reference may be quickly desired. One important object of the invention is realized in the provision of a posting tray having a functionally and structurally improved handle adapted to be conveniently manipulated for tiltably adjusting a swingable plate which may serve either as a follower or compressor member for a stack of sheet material mounted in the tray, the handle adapted to be advantageously utilized as releasing means to permit pivotal displacement of a pair of telescopically associated and hinged members in the matter of tiltably adjusting the swingable plate, the handle also serving as locking means to preclude pivotal displacement of the telescopically associated members after having set the hinged plate in a desired tilttable or non-tilttable position. The invention further comprehends as an important object the provision of a spring controlled handle pivotally mounted on a hinged plate and adapted to actuate a pivoted and hollow guide which slidably guides a toothed and pivoted member cooperating to interlock with a part of the handle to prevent tilttable displacement of the plate after having been set in a desired position and adapted to permit tilttable adjustment of the plate upon withdrawal of the handle from the toothed member. Other important objects, advantages and salient aspects of the invention will appear from the following detailed description considered in the light of the accompanying drawing wherein:

Fig. 1 is a top plan view of the tray shown partly broken away and partly expanded.

Fig. 2 is an enlarged front view of Fig. 1, shown partly broken away.

Fig. 3 is a longitudinal view of Fig. 1, shown partly in section and partly broken away to illustrate the internal construction.

Fig. 4 is an enlarged sectional view on the line 4—4 of Fig. 3 illustrating a portion of the handle interlocked with the companion swingable rack.

Fig. 4a is a view similar to Fig. 4 but showing the handle unlocked from the swingable rack.

Fig. 5 is an enlarged sectional view on the line 5—5 of Fig. 3.

Fig. 6 is a transverse sectional view on the line 6—6 of Fig. 3, and

Figs. 7, 8 and 9 are perspective views of the

2

handle, the tubular guide, and the cooperative locking rack for the latter.

Illustrative of the embodiment disclosed, the tray generally denoted T comprises a sheet metal base or support 10 having the medially arranged depending boss 11 defining a longitudinally disposed channel 12. To the spaced sides 13 of the hollow boss 11 (Figs. 1, 3 and 5) and adjacent the ends thereof, the U-shaped members 14 are appropriately fixedly secured within the channel 12. These U-shaped or channel-shaped members 14 characterize bearing means for rotatably sustaining the cylindrical portions 15 (Fig. 5) of the spaced screws 16 which have their inner cylindrical ends 17 rotatably guided and confined in the bearing block 18 having spaced upstanding sides 19 (Fig. 8) fastened to the spaced sides 13 of the boss 11 by the threaded members 20.

Parallel to and spaced above the aligned and rotatably guided screws 16 within channel 12 is the guide rod 21 which passes through openings 22 in the U-shaped and fixed end bearings 14 secured in the boss 11. This rod also extends through openings 23 in the spaced rectangular shaped blocks or runners 24 each having a threaded bore 25 in mesh with its respective screw 16 (Fig. 3). By the arrangement disclosed rod 21 is slidably sustained by the runners 24. This rod although slidably and removably supported by the U-shaped end bearings 14 is provided with threaded end portions 25' removably sustaining threaded members 26 which are adapted to removably clamp against the front and rear walls 27 and 37 of the base, these walls embodying openings 28 (Fig. 3) for removably receiving the end threaded portions 25'. By this arrangement, guide rod 21 may be removed or disconnected from the base and withdrawn from the spaced runners 24 disposed within the boss 11. Conversely the rod 21 may be quickly threaded through the front and rear walls of the base and through the blocks or runners 24 and held in a fixed relation to the base by the clamping members 26.

The base 10 which is preferably of sheet metal may be said to be characterized by spaced horizontal and flat sections 29 (Fig. 6) bent inwardly from sides 30 and 31 of the base and have their margins 32 desirably welded to the flanges 33 extending outwardly from the sides 13 of the hollow boss 11.

Superimposed on fixedly secured and spaced flat sections 29 of the base are the flat sheet metal panels 39 having the roughened surfaces 40 to prevent slipping of the stack of sheets (not shown) vertically mounted between the spaced swingable follower or leaf 41 and the swingable compressor or leaf 42 each of which is disposed transversely of the base.

Slidably longitudinally of the base but disposed

or rectilinearly displaced severally when its associated non-circular terminal 71 (Fig. 3) is removably engaged and rotated by a coacting socket 72 having a fixed crank arm 73. These brackets are swiveled also on the circular bosses 47 to permit rotation of the plates 41 and 42 about their vertical axis.

Fixedly secured to the upper portions of the tiltable follower 41 and compressor 42 are the brackets 74 each having spaced wings 75 which sustain the fulcrum means 76 on which the spaced perforated ears 77 of U-shaped yokes 78 fixedly carried by the handles 53 are pivoted. The ears or wings 77 in fact are closely straddled by the spaced perforated wings 75 of the brackets 74 and the wings 77 pivotally and closely straddle the upper perforated portions 79 in the spaced sides 61 of the tubular members 54 having aligned openings 80 in which the fulcrum means 76 is disposed. By this arrangement it is apparent that the upper portions 79 of the tubular guide members 54 are also pivotally sustained on their respective fulcrum means 76.

Appropriately anchored to each of the upstanding portions 56 of the spaced handles 53 is a partly bored hollow manipulator or button 81 each retaining a helicoidal normally expanded spring 82 abutting the upper portions of the follower 41 or compressor 42. These springs tend to urge the extensions 58, consequently urging the hand grasping arcuate portions 57 of the handles inwardly, thus normally tending to position the latching portions 65 to snap into opening 63 and overhang the bore 64 of the tube 54. Where the latching portion 65 is within the tube 54 it disengageably interlocks with the walls of a groove or notch 66, thus locking the pivoted and toothed link to the handle 53. Thus the latter is resisted from accidentally releasing or from unlocking due to the action of the springs 82 which always urge the latching means 54 in a direction towards the toothed side of its associated link 55.

Where it is desired to tilt the follower 41 or compressor 42, the curved portion 57 of its handle 53 is grasped by one hand of the operator and the thumb of the same hand is utilized simultaneously to press the associated manipulator 81 against the energy of its spring 82. This action removes the latching means 65 from a groove 66 of the pivoted link or rack 55 and the latter is unlocked (Fig. 4a). This action negatives the tendency of the latch means 65 to be urged towards the toothed faces of its companion lower link 55. Thereafter an outwardly directed thrust is applied to the handle 53 and the follower may be swung or pivoted. If the handle associated with the compressor 42 is so controlled, it may be tilted to a selected position in a similar manner.

Specifically in an unlocked relation of the latching means 65 and the swingable rack or link 55, the guide tube 54 may be actuated by the arm 58 and thus shifted relative to the lower toothed link 55, hence permitting the latter to be progressively telescopically received in the tubular link 54, and the compressor 42 or follower 41, as the case may be depending upon which handle is manipulated, tilts outwardly and downwardly. For tilting the follower or compressor in an opposite direction its respective handle is utilized to actuate the tubular member 54 to withdraw the toothed link 55 therefrom, that is, where the bottom link or rack 55 is progressively withdrawn, its companion follower or compressor is swung or tilted in an opposite direction,

transversely thereof and superimposed on the spaced panels 39 are front and rear and oppositely arranged substantially right angle shaped members or supports generally denoted 43 each of which comprises a horizontal leg 44 and a vertical leg 45. The horizontal legs 44 each bridge the channel 12 and each includes a circular bearing or opening 46 (Fig. 3) rotatably guided on and removably receiving the circular outer surface of an associate annular boss 47 projecting upwardly from the runners 24. Since the lower legs 44 of the brackets are rotatably retained on the bosses 47, these brackets may be said to be swiveled. As illustrated, each boss 47 includes an internally threaded bore which extends downwardly into its respective runner. The threaded shanks of screws 48 adjustably cooperate with the threaded bores of the runners while the enlarged heads of the screws cooperate with the legs 44 to preclude their accidental removal from the annular and hollow bosses 47. If a screw 16 be rotated its runner 24 is slidably and longitudinally displaced along the guide rod 21 and consequently an associated leg, as 44 of the angle shaped members or brackets 43, is correspondingly linearly displaced relative to and longitudinally of the base 10.

Attached to the upstanding leg 45 of the brackets 43 and to the follower 41 and compressor 42 are the hingedly secured plates 50 and 51 having the fulcrum pins 52. By such hinged connection the follower and compressor may be selectively tilted relative to their brackets 43. For purposes of specification the pivoted follower 41 and compressor 42 may be considered as hinged plates for removably clamping a stack of sheet material placed in the tray, and these plates may be swung relative to the base 10 due to the hinged connecting means 50 and 51 carried by the brackets 43.

For controlling the degree of tilt of the follower or compressor an arcuate shaped handle 53 is associated therewith. Each handle is utilized to actuate a tubular but rectangularly shaped member 54 telescopically receiving and slidably guided on the pivoted link 55. Specifically each handle or manipulator 53 comprises a vertical terminal or extension 56 merging with the downwardly and outwardly extending hand grasping curved portion 57 which in turn merges with the inwardly turned and substantially rectilinear arm 58 embodying an elongated substantially rectangular shaped opening 59 having its sides 60 closely but movably straddling the spaced rectilinear sides 61 of tubular member 54. The tubular member 54 has a wall 62 and its associated interconnecting spaced sides 61 provided with a relatively deep notch or gap 63 in which a latching portion 65 of the arm 58 removably projects. The latching portion 65 may be said to be locking means adapted to be severally and removably received in the spaced grooves 66 in the upper part of the swingable link or rack 55 which embodies the spaced arcuately shaped teeth or cams 67 which in part define faces of the grooves 66.

With the latching means 65 disposed in a groove 66 the swingable or hinged link 55 is locked and thus resisted from further tilting. It should be noted, however, that each link 55 has its lower end rotatably mounted on a fulcrum pin 68 carried by the spaced upstanding ears 69 of the spaced angle shaped members 70 which are appropriately fixed to the horizontal legs 44 of the brackets or supports 43. As previously mentioned, either of the brackets 43 may be driven

in fact upwardly. Displacement of a manipulator 81 is limited by its companion follower or compressor and when abutting the latter the latching means 65 is unlocked, that is, removed from toothed link 55 and from the keeper or notch means 63. When finger pressure is removed from the manipulator 81 the latching means 65 is withdrawn from the notch means of the tubular link 54, the spring 82 expands causing the latching means 65 to abut the toothed base of the rack or link 55 and snap into an adjacent groove 66 to automatically interlock with its walls to prevent further tilting of the follower or compressor, thus holding the latter in a tilted but set position. For adjustably tilting either of the hinged leaves 41 and 42, the operator applies finger pressure on a companion manipulator 81 and then applies an outward or inward thrust on the handle 53 for tilting an associated leaf either away from or towards its opposing leaf. To this end and in certain instances, if desired, an inwardly directed thrust on the handle portions 51 only need be applied without actually operating the manipulator 81 for effecting the desired tilt. By such action the handle is also pivoted and the locking means 54 is withdrawn from the toothed link 55 against the energy of spring 82. Even in such instance it is obvious that the handle 53 is unlocked from the toothed link and may be regulated to interlock severally with the notches of the toothed and pivoted link 55 for controlling the extent of tilting of a respective leaf as 41. After having adjusted the tilt, the latching means automatically interlocks with a selected groove 66 due to the expansion of spring 82.

The space or gap 83 between the leaves 41 and 42 may be made longer or smaller by selectively shifting the runners 24 as it is well understood. This space in fact constitutes a compartment for holding a stack of sheet material, such as bookkeeping ledger sheets, record sheets, index cards, etc. During use it is necessary at times to offset a selected sheet from the stack. Thus the width of the tray must be adjusted or compensated for to allow for such offsetting. Also in actual practice it is necessary that posting trays be made fairly compact to occupy relatively small office space. According to the invention provision has been made to permit offsetting of the record cards or sheets without however sacrificing compactness and simplicity in construction. To this end the racks supplementary sheet supporting means generally denoted R are each adapted to be laterally projected relative to the sides 30 and 31 of the base 10.

Specifically each rack comprises spaced and horizontally disposed arms 90 and 91. Extending upwardly from each arm 90 and 91 is a vertical arm 95 desirably coiled around and fastened to rails or rods 96. Thus each rack R embodies a rail 96 attached to spaced vertical arms 95 which in turn merge with the horizontally disposed arms 90 and 91 adapted to be slidably shifted into or out of the base through the spaced slots 97 at the ends of the sides 30 and 31. A vertical arm 90 or 91 and its companion horizontal arm 95 may be said to characterize a bent member or a bent arm.

Various changes may be made in details of construction and arrangement of parts without departing from the spirit of the invention or sacrificing any of the advantages thereof inherent therein.

- I claim:
1. In combination, a base for supporting a stack of sheets, a support disposed transversely of said base, a plate above said support to sustain at least a part of said stack, means swingably connecting said plate to said support, a handle, fulcrum means carried by said plate pivotally supporting said handle, a tubular member pivoted on said fulcrum means and including keeper means, toothed means pivotally sustained on said support and slidably guided by said member, and latching means carried by said handle and removably projectible into said keeper means to disengageably interlock with said toothed means to prevent tilting of said plate relative to said support.
  2. In combination, a base for supporting a stack of sheets, a support disposed transversely of said base, a plate above said support, means swingably connecting said plate to said support, a handle, fulcrum means carried by said plate for pivotally supporting said handle, a tubular member pivotally sustained by said fulcrum means and including keeper means, toothed means pivotally sustained on said support and slidably guided by said member, latching means carried by said handle and removably projectible into said keeper means to disengageably interlock with said toothed means, and spring means acting on said handle for normally urging said latching means to yieldingly bear against said toothed means.
  3. In combination, a base for supporting a stack of sheets, a bracket mounted on and disposed transversely of said base, a plate above said bracket for supporting at least a part of said stack, means swingably connecting said plate to said bracket, a handle, fulcrum means pivotally sustaining said handle, a tubular member rotatably mounted on said fulcrum means, keeper means on said member, toothed means pivotally sustained on said bracket and telescopically associated and slidably guided by said member, and latching means on said handle and removably projectible into said keeper means to disengageably interlock with said toothed means.
  4. In combination, a base for supporting a stack of sheets, a bracket mounted on and disposed transversely of said base, a plate above said bracket for supporting at least a part of said stack, means swingably connecting said plate to said bracket, a handle having an arm including an opening, fulcrum means carried by said plate for pivotally supporting said handle, a tubular member pivoted on said fulcrum means and movably projecting through said opening and including keeper means, toothed means pivoted relative to said bracket and slidably guided by said member, and latching means on said arm adjacent said opening for removably projecting into said keeper means to disengageably interlock with said toothed means.
  5. In combination, a base for supporting a stack of sheets, a support mounted on and disposed transversely of said base, a plate above said support to sustain at least a part of said stack, means swingably connecting said plate to said support, a handle, fulcrum means carried by said plate for pivotally supporting said handle, a tubular member having keeper means, means swingably sustaining one end of said member, a link provided with a toothed portion disposed within and slidably guided by said tubular member, a pivoted connection for tilting said link relative to said support, and latching means sus-

tained by said handle for removably projecting into said keeper means to disengageably interlock with said toothed portion.

6. In combination, a base for supporting a stack of sheets, a support mounted on and disposed transversely of said base, a plate above said support to sustain at least a part of said stack, means swingably connecting said plate to said support, a handle having a latching portion, fulcrum means carried by said plate for pivotally supporting said handle, a tubular member, means swingably sustaining said member, a link provided with a toothed portion disposed within and slidably guided by said tubular member, a pivotal connection to permit tiltable displacement of said link relative to said support, and spring means acting on said handle for urging said latching portion to disengageably interlock with said toothed portion.

7. In combination, a base for supporting a stack of sheets, a support mounted on and disposed transversely of said base, a plate above said support to sustain at least a part of said stack, means swingably connecting said plate to said support, a handle having an opening and a latching portion adjacent said opening, fulcrum means carried by said plate for pivotally supporting said handle, a tubular member disposed within said opening, means swingably sustaining said member, a link provided with a toothed portion and slidably guided by said tubular member, a pivotal connection to permit tiltable displacement of said link relative to said support, and spring means for urging said latching portion to interlock with said toothed portion.

8. In combination, a base for supporting a stack of sheets, a support mounted on and disposed transversely of said base, a plate above said support to sustain at least a part of said stack, means swingably connecting said plate to said support, a handle having an arm including an opening and including a latching portion at said opening, fulcrum means carried by said plate for pivotally supporting said handle, a tubular member within said opening and surrounded by said arm and having keeper means, means swingably sustaining said member, a link provided with a toothed portion disposed within said opening and slidably guided by said tubular member, a pivotal connection to permit tiltable displacement of said link relative to said support, and spring means for holding said latching portion in said keeper means for automatically interlocking with said toothed portion, said latching portion adapted to be removed from said toothed portion permitting said arm to actuate said tubular member to project or retract said link out of or into said member for tilting said plate relative to said support.

9. In combination, a base for supporting a stack of sheets, a support mounted on and disposed transversely of said base, a plate above said support to sustain at least a part of said stack, means swingably connecting said plate to said support, a handle having an arm including an opening and having a latching portion, means pivotally supporting said handle, a tubular member movably guided in said opening and having keeper means, means pivotally connecting said member relative to said plate, a link slidably guided by said tubular member and having a toothed portion, a connection pivotally connecting said link to said support, and spring means acting on said handle to removably sustain said latching portion in said keeper means for yieldingly bearing against

7
8
and to removably interlock with said toothed portion.

10. In a posting tray, a base having a longitudinally disposed channel, a block slidably guided in said channel, bearing means extending from said block, a bracket mounted on said base and bridging said channel and having means rotatably swiveled on said bearing, a plate above said bracket, means swingably connecting said plate to said bracket, and means for linearly displacing said block relative to said channel for correspondingly displacing said plate and bracket relative to said base.

11. In a posting tray, a base having a longitudinally disposed channel, a block slidably guided in said channel, bearing means extending from said block, a bracket mounted on said base and bridging said channel and having means rotatably guided by said bearing means, a plate above said bracket, means swingably connecting said plate to said bracket, rotary means for linearly displacing said block relative to said channel for correspondingly displacing said plate and bracket relative to said base, telescoping and slidably associated link means pivotally interposed between said bracket and plate and including toothed means, a handle pivotally associated with said plate and having means for actuating said link means for tilting said plate relative to said base and having latching means interlocking with said toothed means to preclude said tilting, and spring means for urging said latching means against said toothed means.

12. In a posting tray, a base, a rotatable threaded rod disposed longitudinally of said base, a runner threadably interlocked with said rod and displaceable relative to said base on rotation of said rod, a support having a horizontal leg, a plate mounted above said support, means rotatably sustaining said horizontal leg on said runner, and means tiltably connecting said plate relative to said support.

13. In a posting tray, a base, a runner, means for driving said runner relative to said base, a plate, a support below said plate, hinged means interconnecting said support and plate, and means rotatably sustaining said support relative to said runner.

14. In a posting tray, a base, a runner, means for driving said runner relative to said base, a plate, a support below said plate, hinged means interconnecting said support and plate, means rotatably sustaining said support relative to said runner, and means interposed between and sustained by said support and plate for holding the latter in predetermined tilted positions relative to said base.

15. In a posting tray, a base, a runner, means slidably guiding said runner longitudinally of said base, means for driving said runner longitudinally of said base, a plate disposed transversely and vertically of said base, a support below said plate and disposed horizontally relative to said base, hinged means interconnecting said support and plate, a swiveled connection between said support and said runner, and spring controlled disengageably latching means interposed between said support and plate for maintaining the latter in predetermined tilted position relative to said base.

16. In a posting tray, a base, a runner having an upstanding circular boss, a plate disposed transversely of said base, a support having bearing means rotatably guided by said boss, hinged

means interconnecting said support and plate, and means to retain said support on said boss.

17. In a posting tray, a base having a longitudinal disposed channel, a runner movably disposed within said channel and having a circular boss, means interconnected with said runner for driving the latter, a plate disposed transversely of said base, a support having bearing means rotatably guided by said boss, hinged means interconnecting said support and plate, means to retain said support on said boss, and complementary releasable locking means for tiltably sustaining said plate in predetermined positions relative to said base.

18. In a posting tray, a base, a threaded rod mounted in said base member and disposed longitudinally thereof, a block threadably connected to and mounted on said rod, a support swiveled on said block, a follower leaf hinged to said support, a toothed link having its lower end pivoted to said support, a tubular member having its upper end pivoted on said leaf and slidably receiving said toothed link and having keeper means, a handle comprising latch means receivable in said keeper means and cooperating with said toothed link for holding said follower leaf in a plurality of predetermined angular positions relative to said support, manipulatable means for actuating said latch and disposed adjacent to the top of said follower leaf, and spring means confined within said manipulatable means and coacting with said leaf to removably maintain said latch means within said keeper means for severally interlocking with said toothed means.

19. In combination, a base for supporting a stack of sheets, a support mounted on and disposed horizontally and transversely of said base, a plate disposed transversely of and above said support to sustain at least a part of said stack, means swingably connecting said plate to said support, a handle having an arm including an opening and having a latching portion, means pivotally supporting said handle relative to said plate, a tubular member movably guided in said opening and having keeper means, means pivotally connecting the upper part of said member relative to said plate, a link slidably guided by said tubular member and having a toothed portion, a connection pivotally connecting said link to said support, a manipulatable portion at the upper end of said handle and adjacent said plate, spring means in part within said portion and acting on said plate to removably sustain said latching portion in said keeper means for yieldingly bearing against and to removably interlock with said toothed portion.

20. In combination, a base for supporting a

stack of sheets, a support mounted on and disposed transversely of said base, a plate above said support to sustain at least a part of said stack, means swingably connecting said plate to said support, a handle having an arm including an opening and having a latch portion, a tubular member movably guided in said opening and having keeper means, means pivotally connecting upper portions of said handle and tubular member relative to said plate, a link slidably guided by said tubular member and having a toothed portion, a connection pivotally connecting the lower portion of said link relative to said support, and spring means acting on the upper part of said handle to removably sustain said latching portion in said keeper means for yieldingly bearing against and to removably interlock with the toothed portion.

21. In combination, a base for supporting a stack of sheets, a support mounted on and disposed transversely of said base, a plate above said support to sustain at least a part of said stack, means swingably connecting said plate to said support, a handle having an arm including an opening and having a latching portion, a tubular member movably guided in said opening and having keeper means, means pivotally connecting upper portions of said handle and tubular member relative to said plate, a link in part within and slidably guided by said tubular member and having a toothed portion, a connection pivotally connecting the lower portion of said link relative to said support, a manipulatable portion at the upper part of said handle, and spring means acting on said manipulatable portion and plate to removably sustain said latching portion in said keeper means for yieldingly bearing against and to removably interlock with said toothed portion.
